UNITED STATES PATENT OFFICE

HENRY H. HARDINGE, OF CHICAGO, ILLINOIS, ASSIGNOR, BY MESNE ASSIGNMENTS, TO HARDINGE BROTHERS, INC., OF CHICAGO, ILLINOIS, A CORPORATION OF ILLINOIS

OIL BURNER

Application filed September 5, 1922. Serial No. 586,073.

My invention relates to improvements in oil burners, and is particularly concerned with, though not limited to improvements in that type of oil burner which comprises means for mechanically atomizing the oil, and mixing it with air to form a combustible mixture.

The objects of my invention are:

First: To provide an oil burner comprising a burner unit which can be easily and quickly installed in the furnace to be heated.

Second: To provide an oil burner comprising means, controlled by the pressure of the oil being supplied to the oil burner, for controlling the supply of gas to the pilot light.

Third: To provide an oil burner comprising means for automatically cutting off the supply of gas to the pilot lights after a predetermined interval of time.

Fourth: To provide automatic means for interrupting or opening the circuit of the motor, if for any reason the flame produced by the burner fails to ignite upon the starting of the machine, or is extinguished.

Fifth: To provide an oil burner comprising two units, one a burner unit proper adapted to be located within a furnace, and the other a pump and control unit located outside of the furnace, the two units being connected by suitable pipes so that the control unit can be located at a place desired.

Sixth: To provide a novel type of valve for making it possible to supply oil to the oil burner at an exceedingly small rate; and

Finally: To provide an oil burner comprising means for thoroughly emulsifying the fuel oil before it passes to the atomizing nozzle.

The above and other objects will appear clearly as this description progresses, reference being had to the accompanying drawings, in which

Figure 1 is a vertical section through a furnace equipped with my improved oil

burner, showing the pump unit thereof in side elevation;

Figure 2 is a plan view of the hearth forming part of the furnace, this hearth being particularly adapted to be used in connection with my improved furnace;

Figure 3 is a central longitudinal section through the pump unit of my improved burner;

Figure 4 is a plan view partly in section, showing certain details of construction of the pump and control unit;

Figure 5 is a vertical transverse section taken on the broken section line 5—5 of Figure 4;

Figures 6 and 7 are sectional details, respectively taken on lines 6—6 Figure 4 and 7—7 of Figure 5; and

Figure 8 is a diagrammatic view of the fuel feed system.

Throughout the several views, similar reference characters refer to similar parts, and the several sections are taken looking in the directions of the small arrows.

As indicated above, my improved oil burner in general comprises a burning unit which is located within the furnace, and a pump controlled unit which may be positioned at any desired point outside of the furnace, this unit comprising means for supplying the fuel to the burner unit, and for controlling the supply of fuel to the burner unit, and the operation of the burner unit.

I shall first describe the pump unit, the construction of which is illustrated clearly in Figures 1 to 3, inclusive, and which comprises a base plate 10, which is preferably provided with sharpened lugs 11 which can be driven into the floor so as to prevent the base plate from slipping. A pedestal comprising the base member 12, and the upwardly extending column 13 has a chamber 14 formed in the lower side of the base member, which is closed by the plug 15, these two members having screw threaded engagement

as shown at 16. A sleeve 15a, formed integral with the plug 15 and extending downwardly therefrom, slidably receives the rod 18 projecting upwardly from the knurled head 19 of the adjusting screw 20. A spiral spring 19a interposed between the lower side of the plug 15 and the knurled head 19 provides means for yieldingly supporting the pedestal and the remaining portions of the burner unit. The screw 20 is threaded into the hardened steel ball 21, which is seated in a spherical concavity in the bed plate 10. The ball 21 is held in place by an annular cover plate 22, which surrounds the upper side thereof, and is secured to the bed plate by means of screws 23. A groove 24 is cut in the surface of the ball 21 to receive one end of the pin 25, which is secured in the bed plate 10, and projects into the groove 24 so as to prevent the ball from rotating about a vertical axis when the screw 20 is adjusted to raise or lower the parts supported thereby.

Column 13 of the pedestal is provided with a head 26, the upper surface of which is ground flat, which contacts with a corresponding surface 27 at the lower end of the bearing yoke 28 of the electric motor 29. To secure the head 26 and the surface 27 in close contact, but at the same time to permit the head 26 and the yoke 28 to shift slightly relatively to each other for a purpose which will be referred to later, I provide means for yieldingly securing the head 26 and the yoke together, comprising a plurality of clamping bars 30. The outer end of each of these bars is pivotally mounted on a pin 31 projecting downwardly from the yoke 28, and the inner end of each bar is yieldingly held against the lower side of the head 26 by means of a screw 32, which passes through the bar and into the yoke 28, there being a spiral compression spring 33' located between the head of each screw and each clamping bar 30.

From the above description, it will be clear that the yoke 28, and consequently the motor 29, is free to adjust itself relatively to the pedestal 13, and that it will be yieldingly held by the bars 30 in any of its adjusted positions.

The field frame or housing of the motor 29 is provided with an upwardly extending cylindrical bearing support 33 for receiving and supporting the anti-friction bearing 34. Another anti-friction bearing 35 is supported in the upper side of the cross bar of the yoke 28. These two bearings support the hollow shaft 35 of the rotating element 36 of the motor, which comprises two parts, a main part secured directly to the armature 36, and a hollow spindle extension 35' which is threaded to the main part as shown at 37, and extends upwardly through the anti-friction bearing 34. A cap 38, having the hub

38', threaded on to the spindle 35' provides means for preventing any fuel oil from entering the anti-friction bearing 34.

The outwardly flaring atomizing nozzle 39 is provided with a tubular hub 40, which receives the upper end of the spindle 35'. A pin 41 extending upwardly from the hub 38' is received in a suitable bore in the bottom end of the hub 40, and provides means for causing the atomizing nozzle to rotate with the motor shaft.

Radially extending vanes or blades 42, located on the under side of the atomizing nozzle 39, provide means for creating a blast of air, which is thrown outwardly beneath the atomizing edge 39' of the nozzle to mix with the oil spray thus produced to form a combustible mixture.

A grease cup 44 communicating with a duct 45 in the motor frame provides means for supplying lubricant to the anti-friction bearing 34. A flat ring 46 mounted on the upper side of the cross bar of the yoke 28 carries the brushes 47 which bear upon the commutator 48 of the motor. By this construction, the ring can be adjusted to properly position the brushes 47. An asbestos shield 49 protects the motor from the heat of the furnace, and at the same time provides means for preventing any fuel oil, which might drop downwardly from the atomizing nozzle, from striking the motor and its associated parts.

The column 13 of the pedestal is provided with a vertical bore in which is rotatably mounted a tube 50, the upper end of which is tightly inserted in the lower end of the hollow shaft 35. A disk 51 having bosses 52 on both sides thereof is secured to the lower end of the tube 50 by means of the washer 53, and the nut 54, so as to rotate with the tube 50. The disk 51 rotates in a narrow chamber 55 formed between the base member 12 and the inner end of the plug 15, there being a space of a few thousandths of an inch on each side of the disk 51. This construction is of very considerable importance because I have found that some oils, and particularly those containing a rather large percentage of water and other impurities, if fed directly to the atomizing nozzle will not burn satisfactorily, nor maintain a continuous flame.

I have discovered, however, that by the use of this disk which rotates with the atomizing nozzle a certain amount of emulsification or mixing of the various ingredients of the oil takes place, which entirely eliminates these difficulties.

The tube 50 rotates freely but snugly in the bore of the column 13, and prevents the escape of any more fuel oil along its outside than is necessary to lubricate it, and the anti-friction bearing 35. The clearance between the tube 50 and the column 13 is so small as to prevent any abrasive material from working its way along the outside of the tube and de-

stroying the bearing surfaces. When the motor is started, the tube 50 rotates and almost instantly causes the motor frame and the pedestal to adjust themselves relatively to each other, so as to make the bore of the column 13 co-axial with the shaft of the motor so as to prevent any binding whatever between the tube 50 and the pedestal in which it rotates.

Fuel oil is supplied to the chamber 55 by the feed pipe 56, which communicates with the chamber 55 through the hollow boss 57 and the port 58.

The hearth which I prefer to use with my improved oil burner comprises a plurality of sector shaped plates 60, which are stepped downwardly as shown at 61 to provide a depression 62 (see Figure 1) for receiving fire-clay (not shown), the upper surfaces of the plates being used for supporting a circular row of fire bricks 63, which protect the furnace fire pot. At each end of each plate 60 is an upwardly projecting flange 63'. Bolts or rivets 64 may be used for securing these flanges together so as to make an annular plate which surrounds the atomizing nozzle. Projecting downwardly from the lower side of each sector shaped plate is a hollow boss 65, which receives the upper end of the supporting post 66 which is preferably made of a section of metal pipe. The lower end of the pipe 66 is preferably provided with a bed plate 67.

Mounted upon the inner edge of the ring formed by the sector shaped plates 60 is a hollow ring 68 which is divided by a horizontal partition 69 into upper and lower passageways 70 and 71. The passageway 71 is connected with a gas pipe 72 which continuously supplies gas to the passageway 71, and the upper passageway 70 is connected with a second gas pipe 73, through which the flow of gas is controlled by a mechanism about to be described. Projecting upwardly from the upper surface of the hollow ring 68 are a plurality of cups 74, which communicate with the upper passageway 70 through openings 75 in the collars 76. Each of these collars surrounds a small tube 77, the lower end of which projects through the partition 69 and in to the chamber 71, the tube being held in place by means of a suitable bushing 78. The supply of gas to the passageway 71 is limited so that the flame produced by the combustion of the gas issuing from each of the tubes 77 is entirely confined by the associated cup 74 so as to prevent it from being extinguished. My purpose in providing a plurality of pilot light tubes 77 is to insure that if one of the pilot lights is extinguished some of the remaining ones will remain lighted, and also to insure quick ignition of the oil spray upon the initial production of the spray. As will be described later on, the supply of gas to the passageway 70 is intermittent, but in sufficient quantity to produce flames which will extend

upwardly beyond the tops of the cups 74 a sufficient distance to contact with the oil spray projected from the atomizing nozzle, and cause substantially instantaneous ignition thereof.

A flange 80 extends inwardly from the hollow ring 68, and acts as a support for the neck ring 81, which is centered by the hub 82 surrounding the extended bearing 83 and connected with the lower edge of the neck ring 81 by means of the radial arms 83. Posts 85 project upwardly from the arms 83 and support the flat air ring 86. This ring is provided at its inner edge with a downwardly extending flange 87 that co-acts with the vanes 42 on the atomizing nozzle to produce a fan construction.

In operation, when the atomizing nozzle is rotated the vanes 42 produce a current of air through the ring formed by the flange 87, and between the atomizing nozzle and the air ring. This current of air mixes with the oil projected from the atomizing edge 39' to form a combustible mixture. When this combustible mixture is ignited it heats the air contained in the furnace and causes this air to move upwardly, thus creating a draft through the furnace which induces an additional current of air between the top edge of the neck ring 81 and the outer edge of the air ring 86.

Any increase in the quantity of oil being supplied to the atomizing nozzle will create a more intense flame, thus heating the air within the furnace to a higher temperature, and correspondingly increasing the natural draft through the furnace. This will mean that more air will flow between the neck ring 81 and the air ring 86 to assist in the combustion of the increased quantity of fuel. The regulation of the amount of air required for complete combustion of the fuel is therefore automatic.

For supplying oil to the atomizing nozzle, I provide the electric motor 88 (see Figs. 4 and 5) which is connected by coupling 89 with the shaft of the pump 90, which is preferably of the gear type. This pump receives the fuel oil through the pipe 91, which is connected with any suitable supply of oil such as tank 91a. The pump 90 discharges through a pressure regulating valve 92 which may be of standard construction, but which is preferably of the type which will permit the regulation of the pressure. Preferably, this valve is adjusted to give a pressure of from 25 to 30 pounds in the discharge pipe 93, which leads toward the atomizing nozzle. The excess of oil drains downwardly through the pipe 94 (see Fig. 5) and returns to the supply tank. The oil flowing through the pipe 93 passes through the oil control valve 95 and the cut-off valve 96 into the feed pipe 56.

The control valve 95 comprises a body

member 97 having a conical seat 98, of about 10° taper, formed therein. A small opening 99 extending through one wall of the seat 98 communicates with the pipe 93 and a corresponding, but smaller, opening 100 (preferably about .025 inch diameter), passing through the wall of the seat at a point opposite the opening 99, communicates with the pipe 93' which leads to the cut-off valve 96. The valve 101 which is tapered to fit 10 into the conical seat 98 is mounted upon the shaft 102, which passes through the stuffing box 103 formed integrally with the body member 97 and comprising the gasket 104, the bush 105 and the follower 106. A spring 15 107 interposed between the valve and the shoulder 108 formed on the body member provides means for yieldingly urging the valve 101 outwardly away from the valve seat. 20 A plug 108' closes the open end of the valve seat and is provided with a bore 109, through which the push rod 110 extends upwardly, the inner end of the push rod being 25 in engagement with the end of the shaft 102. A nut 111 is secured to the outer end of posts 112 projecting from the plug 108 by means of screws 113, and carries the screw 114 to the outer end of which is secured an index 30 disk 115, having the knurled hub 116 by means of which the screw can be adjusted. The inner end of the screw bears against the push rod 110.

From the above description, it will be seen 35 that when the screw 114 is adjusted outwardly the spring 107 will force the valve outwardly a corresponding distance and that when the screw 114 is moved inwardly the valve will be moved toward its seat. In this 40 manner, I am enabled to adjust the distance between the valve and its seat, as desired. The valve co-acts with the small opening 100 to control the flow of oil to the burner. It will be apparent that by moving the valve 45 toward its seat the clearance between the valve and the adjacent edges of the opening 100 can be made as small or as large as desired, within certain limits, and thus correspondingly change the flow of oil to the atomizing burner. The constant rotation of 50 the shaft 102, to which the valve is secured, and the friction of any small particles of dirt or sediment which may be in the oil, causes these particles to be moved away from 55 the opening 100, so that there is no clogging or stoppage of this opening. These particles of dirt can move to either end of the valve, and can be removed from time to time by removing the plug 108' and flushing the valve 60 cavity or seat.

For rotating the shaft 102 I secure a grooved pulley 117 to the motor shaft, and connect it by the belt 118 with a grooved pulley 119 on the end of the shaft 120. The 65 shaft 120 is journaled in spaced bearings

121, which are carried by a suitable pedestal 122 projecting upwardly from the bed plate 123. A worm 124, secured to the shaft 120, intermediate the bearings 121, meshes with a worm wheel (not shown) secured to the end 70 of the shaft 102 opposite the valve 101. This end of the shaft is journaled in a bearing 125, likewise supported by the pedestal 122. When the motor 88 is in operation, the motion of its shaft is communicated to the shaft 75 120 by the two grooved pulleys 117 and 119, and the belt 118, and the shaft 120 drives the shaft 102 through the worm 124 and the co-acting worm wheel.

I shall next describe the means by which I 80 control the supply of oil to the burner and the supply of gas to the pilot light. The valve 96 comprises a body member 126 having the bore 127 extending therethrough. This bore is intersected intermediate its ends by 85 the bore 128 in which is slidably mounted the valve 129 having the transverse opening 130 extending therethrough which, in one position of the valve 129 registers with the bore 127 so as to provide a continuous passageway 90 for the flow of oil through the valve. The outer end of the valve 129 has a pin 131 which slides in a radial slot in the arm 132. This arm is provided with a hub 133 which is secured to a shaft 134. The shaft 134 is journaled at its opposite ends in bearings 135 and 136 carried by pedestals 137 and 138 respectively, projecting upwardly from the bed plate 123. Longitudinal movement of the 95 shaft 134 is prevented by means of the end screws 140 and 141. A second radial arm 142 projects from the shaft 134 and is secured thereto. The outer end of this arm is connected by the pivot pin 144 with the upper end of a link 145, the lower end of which is 100 pivotally secured to the upper end of a plunger 146 by means of the pin 147 (see Fig. 5). A cup leather 148 secured to the lower end of the plunger 146 by means of a washer 149 and screw 150 provides means for preventing the 105 escape of oil outwardly along the plunger 146, which is slidably mounted in the cylinder 151. This cylinder projects downwardly through an opening in the bed plate 123, and is supported by an annular flange 152 which engages the top side of an annular boss 153 projecting upwardly from the bed plate. The pipe 154 which is connected with the discharge pipe 93 by the three-way union 155 (see Fig. 4) communicates with the upper 110 end of a passageway 156 formed in the wall of the cylinder 151, so that when the pump 90 places the oil in discharge pipe 93 under pressure a portion of this oil will flow through the pipe 154 and into the lower end of the cylinder 151, thus causing an upward thrust 115 on the plunger 146. The plunger thereupon moves upwardly, and by its connection with the shaft 134 causes the latter to rotate in a direction to move the valve 139 so as to bring 120

125 130

the opening 130 into registry with the bore 127, and thus permit passage of oil through the valve 96 to the atomizing nozzle. A coil spring 142', surrounding the shaft 134 having one end anchored to the bearing 136 and the other end secured to the arm 142, yieldingly opposes the pressure of the oil on the lower end of the plunger 146 and tends to return the plunger to the position shown in Figure 5.

A rod 157 is secured to the shaft 134 by means of a set screw 158 and carries at its outer end a weight 159. The pin 144, which connects the link 145 with the end of the arm 142, operates in an elongated slot 160 in the link 145 which forms a lost motion connection so that when the plunger 146 has moved upwardly sufficiently to tilt the rod 157 slightly past its vertical position it will fall to the position shown in dotted outline in Figure 6 without any further movement of the plunger, thereby quickly bringing the opening 130 in the valve 129 into registry with the bore 127.

The valve for controlling the supply of gas to the passageway 70 in the hollow ring 68 comprises a body member 161 having the chamber 162 formed therein, and a bore 163 which intersects the chamber. At its outer end the bore 163 is reduced in diameter as shown at 163'. The valve comprises the rod 164, which reciprocates in the bore 163, and which has a portion 164' of reduced diameter sliding in the bore 163'. A spring 165 interposed between the body member 161, and a collar 166 secured to the outer end of the valve 164, tends to move the valve 164 outwardly so as to permit the gas to flow through the chamber 162 past the reduced portion 164' of the valve. The gas enters the chamber 162 from any suitable source of supply through the pipe 167, and leaves the opposite end of the chamber 162 through the pipe 73, which leads to the passageway 70.

Secured to the extreme outer end of the valve 164 is an anti-friction roller 168, which contacts with the periphery of the cam 169 having the short lobe 170. When the cam 169 is positioned as shown in Figure 4, the valve 164 is held in its innermost position and the passageway through the chamber 162 is closed, thus shutting off the supply of gas to the passageway 70.

The cam 169 is secured to a ratchet wheel 171 and both are rotatably mounted upon a pin 172, which projects upwardly from the plate 173 which in turn is supported by a post 174, projecting upwardly from the bed plate 123, a nut 175 being used for securing the plate to the post. The ratchet wheel is mutilated by the removal of one or two teeth, as shown at 176. A lever 177 is pivotally mounted on the plate 173 by means of a suitable pivot pin 178, and is oscillated by a pitman rod 179, one end of which is pivot-

ally secured to the lever 177 intermediate its ends, and the other end of which is provided with an eccentric strap 180, which co-acts with an eccentric 181 mounted on the shaft 102, and secured thereto by means of the set screw 182. A pawl 183 is pivotally mounted on the outer end of the lever 177 and is adapted to engage the teeth of the ratchet wheel 171, it being held in engagement with the teeth of this gear in the usual manner by the spring 184.

A second lever 185 is pivotally mounted upon the plate 173, and carries a pawl 186 at its outer end, which is likewise adapted to coact with the teeth of the ratchet wheel 171, and which is held in contact therewith by a spring 187. A link 188 connects the extreme outer end of the valve 129 with a point intermediate the ends of the lever 185, so that when the shaft 134 is rocked to move the valve 129 to its open position the pawl 186 will engage a tooth of the ratchet wheel 171 and give this ratchet wheel sufficient angular movement to bring the pawl 183 into contact with one of its teeth. Since the pitman rod 179 is being constantly reciprocated as soon as the ratchet wheel 171 is brought into a position where the pawl 183 can engage the teeth thereof, it will continue to engage the successive teeth of the ratchet wheel until it has caused this wheel to make one complete revolution, when the pawl 183 will again engage the mutilated portion of this wheel and thus permit it to come to rest in the position shown in Figure 4. However, as soon as the pawl 183 starts to rotate the ratchet wheel, the cam 169 will rotate with the ratchet wheel and almost instantaneously the lobe 170 will pass from beneath the wheel 168, which will thereupon engage the dwell portion of the cam 169, thus permitting the valve 164 to move to its open position. This means that during the period the cam is making almost one complete revolution, the valve 164 will be in its open position, and for this period of time gas is being supplied to the passageway 70 and outwardly through the opening 75 to form igniting flames. These flames are permitted to continue for a sufficient length of time to insure the ignition of the combustible mixture formed by the atomizing nozzle.

If, for any reason, the pressure of the oil in the discharge pipe 93 should fail, the spring 142' causes the shaft 134 to rotate in a direction opposite to that heretofore referred to, and the plunger 146 to move downwardly in the cylinder 151. When the shaft 134 has moved sufficiently to tilt the rod 157 to a position slightly past the vertical, the weight 159 will then become active to force the plunger 146 downwardly in the cylinder 151 and to quickly close the valve 129. This movement of the shaft 134 also causes the link 188 to return the lever 185

and its associated pawl 186 to its initial position so that when the shaft 134 is again rotated in the opposite direction the pawl 186 will be in position to again move the ratchet wheel 171 sufficiently to permit the pawl 183 to engage the teeth thereof.

For the purpose of preventing the flooding of the furnace in the event the flame should, for any reason, be extinguished while the motor is operating and not relighted by the pilot lights, I provide means for automatically interrupting the circuit of the motor, and thus preventing any further discharge of oil from the atomizing nozzle. For this purpose, I place an annular trough 190 below the hearth in such position that any oil discharged from the atomizing nozzle and dropping upon the hearth will drain down the plates 60 and off the inner edges thereof into this trough. The trough is supported by brackets 191, extending inwardly from the posts 66, and is provided with a discharge spout 192 which delivers the oil into a bucket 193 carried by one end of the lever 194. This lever is pivotally mounted at 195, upon a bracket 196, which is here shown as being supported from the pipe 56. A counter-weight 197 provides means for holding the lever 194 in a substantially horizontal position. A cut-off valve 198 has its stem pivotally secured to the lever 194, as shown at 199, at a point intermediate the bucket and the pivot point 195 of the lever. This valve is provided with a passageway 200, which, 35 when the lever 194 is in a horizontal position, registers with the interrupted passageway 201 of the valve body member 202.

A slight amount of oil discharged into the bucket 193 will cause the latter to descend and position the valve 198 so as to cut off the flow of oil through the pipe 56.

The valve 92 comprises the two chambers 92a, which receive the discharge from the pump 90, and 92b which communicates with the return pipe 94 through the valve opening 92c. The valve 92d is yieldingly urged toward its closed position by the spring 92e. Outward movement of the valve stem 92f is limited by the stop screw 92g, which can be 50 adjusted to determine the extent of the outward movement of the valve, and consequently the size of the effective opening between the chambers 92a and 92b. The motor 88 is a constant speed motor, and the movement of the valve 92d is sufficient to compensate for the slight variations in the discharge of the motor due to changes in speed, but the stop 92g is so positioned that it will prevent the opening of the valve 92d, sufficiently to 55 permit the entire discharge of the pump from passing through the opening 92c under the pressure at which the apparatus normally operates. Consequently, when the flow through the pipe 93 is stopped by the closing 60 of the cut-off valve in the pipe 56, the valve

92d cannot open far enough to permit all of the oil discharged by the pump to return to the supply tank under the normal operating pressure. This causes the pressure of the oil in the pipe 205 which communicates with the pipe 93 to increase. The pipe 205 communicates with a cylinder 206, which has a supporting plate 207 that is secured to the bed plate 123, and in which is reciprocably mounted a plunger 208. A suitable gasket 209 secured to the inner end of the plunger 208 by a screw 210 prevents leakage of oil along the plunger. The plunger is held in its innermost position by a compression spring 211, one end of which abuts against the plunger, and the other end of which abuts against the follower 212 screwed in the outer end of the cylinder. The spring 211 surrounds the trip rod 213, the inner end of which is secured to the plunger, and the outer end of which extends through the follower 212 and is beveled, as shown at 214, to provide a cam surface for co-acting with the beveled end of the trip lever 215. This lever is pivoted at 216, and is yieldingly held in engagement with a pin 217 carried by the switch blade 218 to hold the switch blade in contact with the switch clip 219. A tension spring 220 has one end secured to the switch blade 218, and the other end secured to one of the screws 221, which secures the plate 207 to the bed plate 123. When the parts are in the position shown in Figure 4, the spring 20 is under tension.

When the plunger 208 moves outwardly under the pressure of the oil in the cylinder 206, its beveled end 214 causes the trip lever 215 to disengage the pin 217 and permit the tension spring 220 to operate so as to disengage the switch blade 218 from the clip 219. These two elements, that is, the switch blade 218 and the clip 219, form a part of the motor circuit, and when they are disengaged the circuit of the motor is opened, and it comes to a stop. A handle 222, the outer end of which is broken away, is provided for closing the switch. A spring 223 engages the trip lever 215 with the pin 217 when the switch is moved to its closed position.

As soon as the motor stops, the pressure in the pipe 205 and consequently in the cylinder 206 decreases, and permits the plunger 208 to return to its original position under the influence of the spring 211, so that the switch can be closed.

In Figure 5, I have illustrated the bottom of the bed plate 123 as being inclined downwardly toward the right hand side. This is for the purpose of draining the drip oil to the right hand side so that it can drain through the valve opening 225 into the chamber 226, which communicates through the opening 227 with the return pipe 94. I provide the valve 228 for closing the opening 225, this valve being mounted upon the valve

stem 229, the lower end of which is slidably mounted in the hollow, inwardly projecting boss 230 formed on the screw 231.

When there is no pressure in the pipe 94, the valve 228 will be in the open position shown in Figure 5, but if for any reason pressure should be developed in the pipe 94, which would tend to cause the escape of oil through the opening 227 and the valve opening 225, the pressure of this oil upon the lower side of the valve 228 will be sufficient to close it and hold it in its closed position as long as there continues to be any pressure in the pipe 94.

15 While I have described the details of construction of the preferred embodiment of my invention, it is to be clearly understood that my invention is not limited to these details, but is capable of other adaptations and modifications within the scope of the appended claims.

Having thus described my invention, what I claim is:

1. An oil burner comprising a rotary atomizing nozzle, means for supplying oil to said atomizing nozzle comprising a pressure pump having a discharge conduit connected with said atomizing nozzle, a rotary measuring valve interposed in said discharge conduit, an oil cut-off valve interposed in said pressure conduit, means for igniting the oil spray formed by said atomizing nozzle comprising a pilot light, a pipe for intermittently supplying gas to said pilot light to form an ignition flame, a gas cut-off valve interposed in said last mentioned pipe, means for automatically opening said oil cut-off valve when said pump is started, comprising a rocker shaft, a spring biasing said rocker shaft to the closed position of said oil cut-off valve, a cylinder, a plunger reciprocably mounted in said cylinder, an arm extending from said rocker shaft and connected with said plunger by a lost motion connection, the said cylinder being connected by a pipe with said discharge pipe intermediate said pump and said measuring valve, an arm extending from said rocker shaft and pivotally connected with said oil cut-off valve, said rocker shaft being provided with an eccentric weight to bias it to either the open or closed position of said oil cut-off valve when said plunger is actuated in a corresponding direction, means for opening and closing said gas shut-off valve comprising a rotary cam having an extended dwell portion corresponding to the open position of said oil cut-off valve, a ratchet wheel for rotating said cam, a pawl for engaging said ratchet wheel, means actuated by the shaft of said rotary measuring valve for oscillating said pawl, said ratchet wheel having a mutilated portion corresponding to the position of said cam in which said gas cut-off valve is held closed, and a second pawl actuated by said rocker arm to move said ratchet

wheel so as to permit said first named pawl to engage the teeth thereof, the dwell portion of said cam being so positioned relative to the mutilated portion of said ratchet wheel that the fuel cut-off valve will be opened before said gas cut-off valve is opened.

2. An oil burner comprising a rotary atomizing nozzle, means for supplying oil to said atomizing nozzle comprising a pressure pump having a discharge conduit connected with said atomizing nozzle, an oil cut-off valve interposed in said pressure conduit, means for igniting the oil spray formed by said atomizing nozzle comprising a pilot light, a pipe for intermittently supplying gas to said pilot light to form an ignition flame, a gas cut-off valve interposed in said last mentioned pipe, means for automatically opening said oil cut-off valve when said pump is started, comprising a rocker shaft, a spring biasing said rocker shaft to the closed positions of said oil cut-off valve, a cylinder, a plunger reciprocably mounted in said cylinder, an arm extending from said rocker shaft and connected with said plunger by a lost motion connection, the said cylinder being connected by a pipe with said discharge pipe, an arm extending from said rocker shaft and pivotally connected with said oil cut-off valve, means for opening and closing said gas shut-off valve comprising a rotary cam having an extended dwell portion corresponding to the open position of said oil cut-off valve, a ratchet wheel for rotating said cam, a pawl for engaging said ratchet wheel, and means actuated by the shaft of said rotary measuring valve for oscillating said pawl.

3. An oil burner system comprising a nozzle, an oil supply leading to said nozzle, a pump for delivering oil under pressure to said supply, a fuel cut-off valve in said oil supply, a pilot light for igniting the oil in the burner, a gas supply for said pilot light, a chamber surrounding the pilot light, a cut-off valve, a gas supply for said chamber independent of the pilot light gas supply, a cut-off valve in this second gas supply and means operated by the pressure of the fuel for opening the fuel supply cut-off valve and said gas supply cut-off valve, and means for closing said gas supply cut-off valve after a predetermined time interval.

4. An oil burner system comprising a burner nozzle, a fuel supply therefor, a cut-off valve in said fuel supply, a pilot light igniting means in the burner, a gas supply for said pilot light, an independent supply for delivering gas around said pilot light, a cut-off valve in said independent gas supply, a pressure operated device for opening said fuel cut-off valve, means whereby said device also opens the valve in the independent gas supply.

5. An oil burner system comprising a rotary atomizing nozzle for delivering fuel to

- 5 said burner, a supply conduit leading to said nozzle, a pump for delivering oil to said conduit under pressure, a cut-off in said conduit whereby no oil is delivered to the nozzle until 70 a predetermined pressure has been reached, 5 a cylinder connected to said supply between the cut-off and the pump, a piston in said cylinder and means operated by said piston for opening said cut-off valve after a predetermined time interval. 75
- 10 6. In an oil burner system, a rotary atomizing nozzle, a conduit for delivering fuel oil thereto, a pump for supplying said fuel oil under pressure, electrical means for controlling the driving mechanism of said pump and 80 said nozzle, a cut-off valve in said fuel supply, a pressure cylinder connected to said fuel supply between the pump and the cut-off valve and means operated by the liquid in 85 said pressure cylinder for opening the cut-off valve at a predetermined time subsequent to the operation of the electrical control means. 90
- 15 7. A fuel burner comprising a nozzle, a fuel oil supply for said nozzle, a pump for supplying fuel under pressure to said supply, a pilot light for igniting the fuel delivered by the nozzle, a gas supply therefor, an independent gas supply for delivering gas around 95 said pilot light, a cut-off valve in said independent gas supply, means responsive to the pressure of said fuel oil supply for opening said cut-off valve in the independent gas supply and means including a mutilated gear 100 and a cam associated therewith for closing said gas cut-off. 105
- 20 8. In combination, an electric motor, a pump operated thereby, a rotary atomizing nozzle, a conduit for supplying oil from said pump to said nozzle, means for igniting the fuel delivered by the nozzle, a gas supply for 110 said means, a cut-off valve in said gas supply, means operated by the pressure in the fuel supply conduit for opening said cut-off valve, means driven by said motor for maintaining the cut-off valve open for a predetermined period, said means including a mutilated gear 115 and a cam. 120
- 25 9. In combination, an electric motor, a rotary atomizing nozzle for a gas burner, a pump driven by said motor for supplying oil to said nozzle under pressure, a conduit between the pump and the nozzle, a valve chamber in said conduit, a valve in said chamber, 125 means whereby said valve is rotated by said motor, a gas supply for igniting the fuel in said burner, a cut-off valve in said gas supply, means responsive to pressure in the fuel conduit for opening said cut-off valve after a predetermined time interval, means for closing said valve, said latter means being operated by the motor through a ratchet mutilated gear combination associated with a cam. 130
- 30 10. A fuel oil burner system comprising a rotary atomizing nozzle, a fuel oil supply 135 for said nozzle, a pump for delivering fuel to said supply under pressure, a motor for driving said pump, a valve in said fuel supply, means for rotating said valve by said motor, a cut-off valve in said supply, a chamber connected with said supply between the cut-off and the pump, a piston in said chamber actuated by the fluid delivered thereto adapted to open the cut-off valve in the fuel supply conduit, a gas supply for igniting the fuel delivered by the nozzle, a cut-off valve in said gas supply, means connected to the fuel cut-off valve for opening the gas cut-off valve, and means operated by said motor for closing the gas cut-off valve after a time interval sufficient for the ignition of the fuel delivered by the nozzle. 140
- 35 11. An oil burner comprising an operating motor, means for supplying fuel oil to the burner, a cut off valve therefor, an igniting flame nozzle for the burner, means for supplying gas thereto, a cut off valve therefor, a timing mechanism for closing said gas shut off valve and means responsive incident to the rotation of the motor for opening said fuel cut off and for initiating the operation of said timing mechanism to open said gas cut off whereby said timing mechanism will close said gas shut off valve after it has been open for a predetermined time. 145
- 40 12. An oil burner comprising an operating motor, means for supplying fuel oil to the burner, a cut off valve therefor, an igniting flame nozzle for the burner, means for supplying gas thereto, a cut off valve therefor, a timing mechanism for closing said gas shut off valve, said mechanism comprising a mutilated ratchet wheel, a driving pawl actuated by the motor, and an initiating pawl for moving said ratchet wheel and means responsive 150 incident to the rotation of the motor for opening said fuel cut off and moving said initiating pawl to open said gas cut off. 155
- 45 13. An oil burner comprising power driven means for mixing air and oil, an electric operating motor therefor, a gas light for igniting the burner, a gas feed conduit therefor, a valve in said conduit, means responsive to the rotation of said motor for opening said valve and means for closing said valve after a predetermined interval of time comprising a timing wheel, advancing means engaging said wheel and driven by the motor for advancing said timing wheel, a mutilated region in said wheel for rendering said advancing means inoperative and an initiating member actuated in response to the starting of said motor for carrying said mutilated region past the advancing means, and means controlled by the rotation of said timing wheel 160 for closing said gas cut off valve. 165
- 50 14. An oil burner comprising an atomizing device, power means for operating said device, an electric motor for controlling the fuel supply thereto, a gas light for igniting the 170

burner, a gas feed thereto, means for controlling said gas feed comprising valve means, means driven by the motor and adapted when initiated to open said valve means and close 5 the same after a predetermined time interval, and means responsive incident to the starting of the motor to initiate the means whereby the valve means is actuated.

In witness whereof, I hereunto subscribe 10 my name this 27 day of June, 1922.

HENRY H. HARDINGE.
